UNITED STATES PATENT OFFICE.

ARTHUR S. TREW, OF PORTLAND, OREGON.

AUTOMATIC PNEUMATIC CARD-ASSORTING MACHINE.

1,287,142.

Specification of Letters Patent. Patented Dec. 10, 1918.

Application filed May 8, 1917. Serial No. 167,264.

To all whom it may concern:

Be it known that I, ARTHUR S. TREW, a citizen of the United States, residing in the city of Portland, county of Multnomah, and State of Oregon, have invented certain new and useful Improvements in Automatic Pneumatic Card-Assorting Machines, of which the following is a specification.

My invention relates to automatically controlled card assorting machines of the character shown and described in my pending application filed February 4, 1915, under Serial Number 6,159, in which cards are ejected from a container one by one and automatically transferred into different pockets, a selective mechanism being automatically operated with the ejection of each card to determine the pocket into which that card is to be deposited. In said machine the mechanisms are automatically controlled by manually operated keys corresponding in number to the pockets into which the cards may be deposited, the operation of a key causing the operation of the ejector and also the operation of the selective mechanism, the propelling or carrying mechanism for the cards being continuously operated.

Among the salient objects of the present invention are,—to provide in a card assorting machine a pneumatic mechanism for automatically controlling the operation of the ejector and of the selective mechanism thereof; to provide an automatic pneumatic mechanism adapted to be used with the key-board of a manually operated machine of the character referred to for automatically manipulating said keys; to provide a pneumatic machine of the character referred to which is automatically controlled by the cards being distributed, whereby each card causes the automatic operation of the necessary mechanism to deposit that card into the proper pocket, and also causes the operation of the ejector for ejecting another card into a position for setting in operation the pneumatic automatic mechanism; to provide in a machine of the character referred to means adjustable relative to the card, whereby the record punched in said card, no matter in which of a variety of positions therein, will operate to control the operation of the automatic pneumatic mechanism; and, in general, to provide in a machine of the character referred to automatic pneumatic mechanism, controlled by a punched record in the

card, for automatically assorting and distributing cards.

In order to fully explain my invention I have illustrated one practical embodiment thereof in the accompanying three sheets of drawings, which I will now describe.

Figure 1 is a top plan view of a card assorting machine embodying my invention;

Fig. 2 is a vertical sectional view, taken longitudinally of Fig. 1, on the line 2—2; 65

Fig. 3 is a fragmentary, irregular, vertical sectional view, taken on line 3—3 of Fig. 2;

Fig. 4 is a top plan view of certain driving connections, taken on line 4—4 of Fig. 2;

Fig. 5 is a vertical sectional view, taken 70 on line 5—5 of Fig. 2;

Fig. 6 is an enlarged side elevation, partly in section, as on line 6—6 of Fig. 1, or a magnet-controlled valve for controlling an air passageway, showing the valve closed 75 and an exhaust open at one side of the valve;

Fig. 7 is a similar view showing the valve open for the passage of air through the passageway;

Fig. 8 is a front view of the adjustable 80 pneumatically-operated mechanism, in position over the key-board for operating the keys, said mechanism being shown in top plan view in Fig. 1, and shown swung away from the keys in dotted lines in said Fig. 1; 85

Fig. 9 is a top plan view of the key-board also showing a general release key;

Fig. 10 is a face view of a card with certain records punched therein;

Fig. 11 is an enlarged fragmentary view, 90 with parts broken out, showing a card in position relative to the pneumatic mechanism controlled by the card; and

Fig. 12 is a diagrammatic view showing the electrical connections by means of which 95 the ejector and the switches to the various pockets are controlled.

Referring now in detail to the drawings, my invention as here illustrated comprises a supporting table composed of the end leg 100 members 1—1, with a lower table 2, an intermediate table structure 3 and a top table structure 4.

I will first describe the card container mechanism and the ejector for ejecting the 105 cards therefrom one by one. Referring to Figs. 1 and 2, there is an opening through the table top 4, within which travels a card carriage 5, moving transversely of the table top 4, upon supporting strips, or tracks, 110

6-6, at opposite sides within said opening. Said card carriage 5 is moved forwardly by a weight 7, suspended from a cord 8, which runs over a pulley 9, and is connected with 5 the rear, or back wall 5^a of said card carriage 5. The cards C are set edge-wise upon said card carriage 5, and are adapted to be ejected laterally, one by one, from the front, by means of an ejector 10, mounted in supporting standards 11-11, said ejector being operated by means of a lever 12, pivotally mounted as at 13, on the intermediate table 3, and being normally held, in its back position, as shown in full lines, Fig. 2, by 15 means of a spring 14, one end of which is attached to a downwardly depending member 15. A magnet 16, has its core 17 connected with said lever 12, as at 18, whereby said lever 12 and the ejector 10 can be intermittently operated as the magnet 16 is energized, in a manner hereinafter referred to. Two contact members 10^a and 10^b are mounted on the support 11, Figs. 2 and 12, and are included in a circuit hereinafter 25 more particularly referred to, said contact members being adapted to be moved apart to open their circuit by the engagement with the contact member 10^b of the end of the ejector 10 each time it is moved to eject a 30 card.

Mounted through the table top 4, and the intermediate table 3, are a number of shafts 19, 20, 21, 22 and 23, on the upper ends of which are mounted, respectively, large feed 35 rollers 19', 20', 21', 22' and 23'. Mounted upon the lower ends of these shafts are driving pulleys 19^a, 20^a, 21^a, 22^a and 23^a. Mounted adjacent each of the large rollers, are small rollers designated, respectively, 24, 25, 26, 27 40 and 28, said small rollers being mounted upon crank-like members 24', 25', 26', 27' and 28', on the upper ends of shafts 24^a, 25^a, 26^a, 27^a and 28^a, being provided at their lower ends, above the intermediate table structure 45 3, with springs 29, which operate automatically to hold the small feed rollers 24, 25, 26, 27 and 28, respectively, into engagement with the large feed rollers 19', 20', 21', 22' and 23'. Mounted on the under side of the 50 intermediate table 3, are idle guide pulleys 30-30. Also mounted on the under side of said intermediate table structure 3, in vertical planes, are two guide pulleys 31-31. A driving belt, or cable, 32, is threaded 55 around the various pulleys, is shown in Figs. 2 and 4, and around a driving pulley 33, of a motor 34, mounted upon the bottom table 2, whereby said motor drives the large feed rollers 19', 20', 21', 22' and 23' in the same 60 direction, the large feed rollers 19' and the small feed rollers 24, being positioned at the side of the card carriage, whereby the ejected cards are ejected between said rollers 19' and 24, and are fed forwardly between the 65 other pairs of rollers.

Mounted upon the table top 4 is a back wall member 35, through suitable openings in which the large feed rollers 21', 22' and 23' project sufficiently so that their peripheral engagements with the small rollers 70 26, 27 and 28 are in alinement along the front face of said back wall 35. Pivotaly mounted upon said table top 4, as at 36-36, are switch members 37-37, at a space from the back wall 35, whereby to provide a passageway along said back wall 35, and between it and the switches 37-37, said switch members 37-37, being adapted to be drawn toward said back wall 35, with their front ends seated in notches 35' in said back wall, 80 whereby cards passing along the passageway are deflected into card receiving pockets 38, 39 and 40, separated by the partition members 41-41, and each of said pockets having therein a movable back wall, or 85 bumper, 42, movable in the slots 43-43, in the bottoms of said pockets 38, 39 and 40. Beater members, as 44, 45 and 46, are mounted adjacent the switch members 37-37, for the purpose of beating the cards 90 back into the pockets and against the movable back walls 42-42, as they are discharged into the several pockets. Said beater members are mounted on the upper ends of rods 44', 45' and 46', attached at 95 their lower ends to a rock shaft 46^a, provided with an arm 46^b, connected by means of a link 46^c to a little crank wheel 46^d on the upper end of the shaft 30', on the lower end of which is mounted one of the pulleys 100 30, as shown in Fig. 5, whereby said beaters are oscillated for beating the cards back into the pockets as they enter the same.

Flexible contact members 47, 48 and 49, engage at their free ends with the switch 105 members 37-37, so as to make electrical contact therewith, as hereinafter described, said contacts being adapted to be broken by the passing of a card between the end of the switch members 37-37, and the contact 110 members 47, 48 and 49, as the case may be, when the switch is closed, for a purpose hereinafter referred to.

Mounted at the back of the back wall 35, are magnets 50, 51 and 52, with switch, or 115 relay contact, members 50', 51' and 52' at their back ends, their cores being extended through the back wall 35, whereby as said magnets are, respectively, energized, in a manner hereinafter described, they will attract the switch members 37-37, and draw them across the passageway along the front of the back wall 35. The switch member 37', to the last pocket 40, it will be noted by reference to Figs. 1 and 12, is permanently 120 set across the passageway so that cards going as far as feed rollers 23' and 28 will be directed into pocket 40, and while the magnet 52, when energized, does not move the switch member 37' for the cards, it does 130

operate with its contact switch 52' in the control of the various circuits, hereinafter again referred to.

The mechanism so far described, and the 5 operation thereof, is substantially the same as that shown and described in my pending application filed February 4, 1915, Serial Number 6,159, and to which reference is hereby made.

10 Mounted on the table top 4, at a space apart, are two vertical wall or guide members 53—53, shown clearly in Fig. 3, above which is a top guide strip 54, between which wall members 53—53 and under said top 15 strip 54, move, one by one, the cards C, ejected from the card carriage and brought to a position between said wall members 53—53, by the two large feed rollers 19' and 20', and their coöperating small, spring-pressed rollers 24 and 25; as will be clear from Fig. 1.

Mounted upon the table top 4, at a space apart, are vertical tubular supporting members 55—55, within which are mounted supporting rods 56—56, between the upper ends 25 of which is supported a cross gage bar 57, upon which is adjustably mounted a pneumatic selective device 58, adapted to be held in different positions on the cross gage bar 57, by a trigger-like member 59, as clearly 30 seen in Figs. 2 and 3. Said cross gage bar 57, can be raised and lowered and held in different positions by means of spring catches 60—60, adapted, when said gage bar 57 is in its uppermost position, to hook over 35 the upper ends of the supporting rods 56—56, as shown in Figs. 2 and 11, said cross gage bar 57, when lowered, being adapted to rest upon the upper ends of the tubular members 55—55. The head of said movable 40 selective device, it will be noticed from Figs. 2, 3 and 11, is provided with two rows of holes, as 58', there being ten holes shown, representing ten different positions numbered 0 to 9, inclusive, the lower right hand 45 hole representing 0, and the ones above representing in order 1, 2, 3 and 4, while the holes in the other vertical row, from bottom to top, represent positions 5, 6, 7, 8 and 9. The inner face of said head 58 is flat and is 50 adapted to rest adjacent the face of a card C when said card is moved to the selective position, as in Figs. 1, 2, 3 and 11, Fig. 11 being an enlarged view from the card side, with a portion of the card broken out to show 55 the card-engaging face of the head 58. Attention is here called to the fact that the record on the cards C is made by means of small holes, punched in the different positions in different rows across the card, there 60 being five different positions vertically, in each of two columns of positions corresponding to the two vertical columns of holes through the pneumatic selective head 58. When the cross gage bar 57 is in the position 65 shown in Figs. 2 and 11, and a card is moved

into position against said head 58, the upper series, or the holes in the upper horizontal row on the card will come within the scope of the holes in the head, and when said cross bar 57 is lowered to its down position, so that 70 it rests upon the upper ends of the tubular members 55, the lower series or the holes in the lower horizontal row on the cards C will come within the range of the holes in said pneumatic selective head 58. Said head 58, 75 is adjustably along the gage bar 57, to different positions, corresponding to the different headings or columns in the different horizontal rows across the card.

As a card is ejected and fed forwardly to 80 the selective position shown, it is stopped by means of a gate 61, attached to the core 62, of a magnet 63, whereby it can be moved across the path of the card just before the card reaches the large feed roller 21', and 85 its small roller 26, as shown clearly in Fig. 1, said card at its opposite end standing between the rollers 20' and 25. This stopped, or selective, position is only momentary and is the same for each card. The magnet 63, 90 is connected in electrical circuits hereinafter referred to.

Forming a part of said pneumatic selective device 58, is a magnet 64, supported in a bracket, arm 65, extended rearwardly and downwardly to a position on the opposite side of a card C, as clearly shown in Fig. 3, the core of said magnet having attached thereto a recessed member 66, the recess, or pocket 67 of which has connected thereto a 100 flexible air pipe 68, extended to and connected at its opposite end with an air pump, or any source of air under pressure, said pipe having interposed therein a magnetically-operated valve mechanism, shown in 105 Figs. 6 and 7, and comprising a valve casing 69, having hose connections at its opposite sides, designated 70—70, within which valve casing 69, is a valve member 71, provided with a valve groove 72, within said 110 valve casing 69; and adapted to be moved into and out of register with the passageway formed by the hose connections 70—70, said valve member 71, being connected to the core 73, of a magnet 74, whereby as said 115 magnet is energized its core 73, is drawn inwardly and said valve member 71 is moved downwardly, as shown in Fig. 7, so as to bring the valve groove 72, into register with the passageway through the hose connections 70—70, thus opening the air passageway through the air pipe 68. The valve member 71, is provided in its lower end with an angular exhaust opening 75, extended 120 upwardly into its lower end and through its side, as clearly shown in Fig. 6, said angular exhaust opening being in position to open one side of the valve member 69, through a bottom outlet 76, in the lower end of said valve member, when said valve member 71 is 130

raised, as shown in Fig. 6. Mounted in the lower end of the valve casing 69, is a spring 77, which normally operates to hold said valve member 71 in its raised position which 5 closes the passageway through the air pipe 68, connected with the connections 70—70 of said valve member 68.

The magnet 64 is also provided at its rear end with a contact switch member 64^a, for 10 making contacts between the contact members 64^b and 64^c, in a circuit hereinafter more particularly described. Said contacts are made and the circuit completed when the magnet 64 is energized, as seen in Fig. 3.

15 Connected with each of the holes 58' of the pneumatic selective device 58, is a series of flexible air tubes 78, extended to and connected with a key-operating block 79, pivotally mounted upon the table top 4, as at 80, 20 whereby said key-operating block 79 can be swung around from the positions shown in Figs. 3 and 8, to the position shown in dotted lines in Fig. 1. The key-operating block 79 is provided in its under face with two rows 25 of openings, or chambers, as 79', in which are mounted piston-like members 81—81, having stems 82, which piston-like members are normally held in raised, or up, positions by means of coiled springs 83, mounted on 30 the stems 82, and bearing at their lower ends upon a bottom plate 84, forming a closure for all of the openings 79' in the block 79. There is provided in said key-operating block a plunger, or piston, as 81, for each 35 key of a keyboard 85, through which is mounted the keys 86, of which there are 10 shown in the present embodiment of the invention, with a general release key R. The keys 86 are each provided, underneath the 40 keyboard 85, with a collar 87, Fig. 3, under which, on the key stem, is a coiled spring 88, bearing at its lower end upon a supporting plate 89, through which the key stems project. Mounted in a supporting plate, or 45 shelf 90, suspended to the table top 4, is a series of contact members 91, with which the lower ends of the keys 86, contact when depressed, whether depressed by the fingers, or by the piston-like members 81, in the key-operating block 79, which are depressed by 50 the admission of air through the tubes 78, to the chamber 79', as will be clear from Fig. 3. The release key R extends through the table top 4, and through the shelf and is provided at its lower end with an L-shaped end R', forming a contact adapted to be connected into the circuits hereinafter referred to. The contact end of said release key R is normally held in contact with the contact member 92, which is also connected into a circuit 55 hereinafter referred to, by means of a coiled spring 93, between the keyboard 85 and said key top R. The other keys 86, are also held in their up or normally open positions by 60 means of similar springs 94.

Two relay magnets 94' and 95' are mounted on the lower table 2, each having contact members 94^a and 95^a connected in circuits hereinafter more particularly described.

I will next describe the various electric 70 circuits which operate in connection with the actuation of the various mechanisms hereinbefore described, and for this purpose refer to Fig. 12 of the drawings in which the parts are shown in connection with the dia- 75 grammatic view showing these electric circuits and their connections. In this view no circuit is shown for the motor 34, shown in Fig. 2, which drives the card propelling mechanisms, as this motor may be controlled 80 from a separate circuit and the card propelling mechanisms may be running independently of the other parts of the machine. In Fig. 12, S designates a switch in the main circuit C', which circuit extends to and 85 through the magnet 64, which moves the recessed member 66, up against the card C, shown in dotted lines in Fig. 12, said circuit extending thence through two contact members 96 and 97, between which the cards pass 90 from the ejector, thence through the contact members 10^a and 10^b, adapted to be operated by the ejector 10, and thence back to the switch S. When said circuit is closed it energizes the magnet 64, which moves the recessed member 66, against the card C, and 95 also operates to close its switch 64^a, and thereby completes a circuit C², to and through the magnet 74, which operates the valve member 71, shown in Figs. 6 and 7. 100 Said circuit C², after passing through the switch member 64^a, connects again with circuit C', just before said circuit C' connects with the contact members 96 and 97. With the card C in the position shown in dotted 105 lines, and with the recessed member 66 moved up against the card, which bears against the pneumatic selective device 58, and the valve 71, being opened by magnet 74, air is permitted to pass through the tube 110 68, into the recess 67 of said member 66, and through a record hole in the card C, which is in register with one of the holes in the pneumatic selective head 58, according to the record punched in the card, which air, 115 being admitted to the key-operating block 79, through one of the flexible tubes 78, depresses one of the piston members 81, in said key-operating block 79, and thereby depresses one of the keys 86, of the keyboard 120 85, which key makes contact with one of the contact members 91, directly under the keys, as clearly indicated in Figs. 3, 8 and 12. When the switch S is closed, in addition 125 to establishing the circuit C' and the branch circuit C², there is also established a circuit C³, which extends from the circuit C' through the release key R, its contact member 92, to the magnet 94, thence through the contacts and switch members, designated in 130

order, 47, 37, 48, 37, 49 and 37', and again to circuit C', as will be easily followed on the diagrammatic view.

The energizing of magnet 94, by this circuit C³, closes its switch member 94^a, and establishes another circuit C⁴, up to and through the keyboard 84, and the keys 86, and thence through one of the contact members 91, depending on which key is depressed, and thence through the lines C⁵, C⁶ or C⁷, as the case may be, to the magnets 50, 51 or 52, from which there is connection through a line C⁸, to the magnet 16, which operates the ejector, thence to the relay 95, and thence to the main circuit C¹. This circuit energizes magnet 95, and closes its switch member 95^a, whereby a circuit C⁹ is established from the circuit C¹, near the contact members 96 and 97, through the switch lever 95^a, and thence to magnet 63, and to the main line C¹, which circuit energizes magnet 63 and operates to open the gate 61, allowing the card C to be fed forwardly. When any one of the magnets 50, 51 and 52 is energized, for the purpose of opening one of the switches 37, for the cards, said magnets operate, respectively, to immediately close their contact levers 50', 51' and 52', thereby establishing shunt circuits 5^c, 6^c and 7^c, around the keyboard, which shunt circuits take the places, respectively, of the circuits C⁵, C⁶ and C⁷, for the purpose of maintaining the circuits through the magnets 50 and 51, for holding the switches 37 open, until the card passes said switch into the pocket controlled thereby.

When the magnet 74 is energized, as hereinbefore described, it operates the valve 71, for admitting air through the pneumatic selective devices 66 and 58, and thence to the key-block 79, whereupon one of the keys 86 is operated, depending upon the position of the record-punch in the card, and with which of the air passageways in the head 58 it is in register. Assuming that the first, or left-hand key 86, in Fig. 12, is depressed until it contacts the member 91, the circuit C⁵ is established to magnet 50, and thence to the connecting line C⁸, thence to the ejector magnet 16, thence to the relay 95, and to the main circuit C¹, is completed, which circuit energizes magnet 50, which opens its switch 37, controlling the admission of cards to the pocket 38. It also closes the shunt, or substitute circuit 5^c through the magnet 50. It also energizes the ejector magnet 16, and causes the ejection of another card. It also energizes the magnet 95, which closes the switch 95^a, and establishes the circuit C⁹ through magnet 63, which operates to open the gate 61, and allow the card C standing thereagainst to pass through the switch 37, which has been opened, and into the pocket 38. As the card passes into the pocket 38, it passes between the contact

member 47 and the open switch 37, thus momentarily breaking the circuit C³, which results in deenergizing magnet 94, allowing its switch 94^a to open and thereby also opening circuit C⁴, through the keyboard to circuit C', and consequently all connections therefrom to any of the circuits C⁵, C⁶ or C⁷. It also opens the shunt, or substitute, circuits 5^c, 6^c and 7^c, which results in deenergizing the switch magnets 50, 51 and 52, and the ejector magnet 16; and the relay magnet 95, releasing the switch lever 95^a.

When the ejector 10 was moved forwardly by its magnet 16, it operated to move the contact 10^b, away from the contact 10^a, and thereby also opened the main circuit C¹, through the contacts 96 and 97, and to the magnet 64, and thence around to switch S. This resulted in releasing the recessed member 66, from against the card C. It also released the contact lever 64^a of said magnet 64 and opened the circuit C², which deenergized magnet 74 and closed the air valve, thus cutting off the air through the air tube 68. The opening of the main circuit C¹ by the movement of the ejector 10, also opened the branch circuit C⁸, to the gate magnet 63, which allowed the spring on its core 62, to thrust said core forwardly into a position to stop the next card. The same operation is repeated with the ejection of the next card through the contacts 96 and 97.

Therefore, assuming that we have a quantity of cards, such as shown in Fig. 10 of the drawings, to be assorted into different groups, according to certain of the information listed thereon by means of the record punches therein, said cards are placed edge-wise on the card carriage 5, as shown in Figs. 1 and 2. The gage bar 57, and the pneumatic selective head 58, are set so as to bring the face of said selective head 58, having the holes 58' therethrough, so that said two columns of holes therethrough will be positioned over that portion of the card containing the particular information which it is desired to separate, or classify. Referring to the sample card, shown in Fig. 10, these cards are made by a card-making machine, an application for patent for which is soon to be filed, which card making machine, in its operation, not only prints a number under the proper heading, but also punches a hole in the position corresponding to the hole in the head 58, which occupies that numbers' position. For example, referring to the card, Fig. 10, under the first heading "Form", there are two columns for figures. The figure 3 is printed in the second column, and also a hole is punched in the 3 position above, according to the numbering of the holes 58' in the head 58. The lower right hole is 0, and the one above it is 1, numbering from bottom to top. There is also shown a hole to the left of the 3. This

represents a 0 in the first column. The card making machine always punches a hole in the cipher position in each column when a cipher or no figure is printed in the particular column, thus avoiding manual operation of the keys for the ciphers, as is customary in adding machines.

Referring to the fourth column or field "Sta. FM." or Station from, there are four figures, 7190, the cipher of which is not printed, but is indicated by a hole, as above explained. For each 719, a hole is also punched in connection therewith in the proper positions. If, for example, the 10 cards are to be assorted according to the information listed under the heading "Sta. FM.", it would be necessary to run the cards through the machine four different times, first according to units, then according to 15 tens, then according to hundreds and then according to thousands. The selective head 58 would be set, successively, to these different positions, first over the "unit" columns and all of the cards run through the machine. They would be separated into the 20 ten receiving pockets. All the ciphers in the unit columns would be deposited in the cipher pocket. All the 1's in the unit columns would be deposited in the 1 pocket, 25 and so on. These cards would then be taken from the pockets and put together in numerical order according to bunches from the pockets 0 to 9, and they would be run through the machine again with the 30 pneumatic selective head 58 set so that the two columns of holes 58' overlie the "tens" columns. The cards are again grouped numerically according to their pocket numbers and run through the machine again 35 with the head 58 set in "hundreds" column. The same operation is necessary with the selective head set over the "thousands" column. After the cards have thus been run through the machine they are all arranged 40 in numerical order. All cards having 7190 under the heading "Sta. FM." would come together, and if there was more than one of any other number under this same heading they would all come together. It will be 45 understood, of course, that these cards are run through the machine automatically and very rapidly, and are automatically and pneumatically assorted to the different pockets by the pneumatic selective mechanism in 50 less time than it takes to write it.

During the operation of the machine each card is stopped by the gate 61, in the same position, between the members 66 and 58, long enough for the pneumatic selective 55 mechanism to operate therethrough. After the cards are placed on the card carriage, and the switch S is closed, assuming that the motor 34 is running and operating the card propelling rollers, the first card is started 60 by the movement of the ejector 10, by hand,

which ejects a card between the rollers 19' and 24, which throw it forwardly between the rollers 20' and 25, into the position shown in dotted lines, Figs. 1 and 12, where it is held by the gate 61, which is the position in 65 which each card is stopped long enough for the pneumatic selective mechanism to operate. With the first card thus started and stopped, circuit C¹ is closed by the closing of the main switch S, which circuit energizes 70 magnet 64, and moves the recessed member 66 up against the card, whereby the card then is held between the member 66 and the selective head 58, as shown in Fig. 1. Through the energizing of magnet 64, its 75 switch 64^a, is also closed, closing circuit C², which energizes magnet 74 and opens the valve 71 for the admission of air to the recessed member 66, from which it passes 80 through a record hole in the card, through the selective head 58, and through one of the tubes 78 to the key-operating block 79, where it operates one of the pistons 81, which depresses one of the keys 86, for the purpose 85 of closing one of the circuits C⁵, C⁶ or C⁷, as 90 before described, thus causing the actuation of the proper switch controlling the entrance to the pocket into which the card thus held by the gate 61 is to be deposited as soon as 95 released, and also causing the actuation of the ejector for ejecting another card to take its place against the gate, each card being stopped by the gate sufficiently long to cause the pneumatic selective mechanism to be operated for the purpose of causing the operation 100 of the proper key, each of which controls the operation of a pocket switch, and the ejector. By thus pressing one of the keys 86, circuit C⁵, C⁶ or C⁷ is established, as the case may be, through the corresponding magnet 50, 51 or 52, for opening the proper pocket switch 37. With the energizing of 105 any of the magnets 50, 51 or 52, their switch levers 50', 51' and 52' are closed for the purpose of establishing the substitute or holding circuits, 5^c, 6^c or 7^c, through the magnets 50, 51 and 52, for keeping said magnets energized, when circuit C⁵, C⁶ or C⁷ is opened by the releasing of the key. These circuits C⁵, 110 C⁶ or C⁷, or their substitute circuits 5^c, 6^c or 7^c, are continued through the line C⁸ to the ejector magnet 16, and to the relay magnet 95, and by the closing of its switch 95^a there is established circuit C⁹, through the magnet 63, which operates to withdraw the 115 gate 61, simultaneously with the ejection of another card by the ejector 10, which is operated by the energizing of its magnet 16. The passing of the card between the contact 120 47 and the switch 37, into the pocket 38, as 125 before described, momentarily breaks the circuit C⁸, and deenergizes magnet 94, opens the circuit C⁴, through the keys, which circuit connects through said keys with either of the circuits C¹, C² and C³, which results in open- 130

ing the circuit C^8 , which is really a continuation of circuits C^5 , C^6 and C^7 , to the magnet 95. This opens circuit C^9 at the switch 95^a, deenergizing the magnet 63, so that the gate 5 will be thrust forward by its spring to stop the next card ejected by the ejector 10. The action of the ejector also opens circuit C^1 , which deenergizes magnet 64, and magnet 74, cutting off the air supply for the pneumatic selective mechanism, and thus restores all parts to their normal positions. The card ejected, however, by this movement of the ejector, after passing between the contact members 96 and 97, to its stopped position at 10 the gate 61, allows said contact members 96 and 97, in circuit C^1 , to be again closed together so as to reestablish circuit C^1 , with a repetition of the operations just described.

Thus the machine operates automatically 20 to eject a card, to set in operation the automatic pneumatic selective mechanisms, which operate the keys controlling the switches to pockets into which the cards go, and the ejector, the machine continuing to operate so 25 long as there are any cards on the card carriage to be ejected, and to be fed between the contact members 96 and 97, to the stopped position against the gate 61, as shown in Fig. 12.

30 By swinging the key-operating block 79 out from over the keyboard, in the manner indicated in dotted lines, Fig. 1, the keys are free to be manipulated by hand, according to the corresponding pockets into 35 which the cards go. This can be determined by the printed information on the card, such information being indicated for pneumatic automatic action by the holes properly positioned, and for manual operation by the 40 figures printed thereon, corresponding to the record punches, as before described.

So far as I am aware, I am the first to provide a card-handling machine in which the 45 operation of the card-handling mechanisms, no matter how actuated, is pneumatically controlled, or in which a pneumatic controlling means is provided, which operates through holes punched in the cards, the position 50 of the hole in the card automatically determining the disposition of the card, and while I have shown and described one practical embodiment of my invention in which most of the card-handling mechanisms are electrically operated, I am aware that my invention 55 can be embodied in a great variety of card-handling machines, and I do not, therefore, limit my invention, except as I may be limited by the hereto appended claims.

I claim:

60 1. In a card-handling machine, means for holding a quantity of cards having record holes punched therethrough, means for assorting said cards, and pneumatic controlling mechanism therefor, said pneumatic controlling mechanism operating through

the holes in said cards, whereby to determine their assortment by the positions of their record holes.

2. In a card-handling machine, means for holding a quantity of cards having record 70 holes punched therethrough, means for automatically assorting said cards, and pneumatic means automatically controlling said assorting means, said pneumatic controlling means operating through the record holes in 75 said cards, whereby to assort the same according to the positions of the record holes therein.

3. In a card-handling machine, means for holding a quantity of cards having record 80 holes punched therethrough in different positions, means for assorting said cards comprising an ejector, card-transferring means and card-receiving means, and pneumatic means operable through the record holes in 85 said cards for determining their assorted positions in said card-receiving means.

4. In a card-handling machine, in combination, means for holding a quantity of cards having record holes punched in different positions therein, means for assorting 90 said cards comprising an ejector, card-transferring means and card-receiving means, and a pneumatic controlling mechanism operating through the record holes punched in 95 said cards and adapted to control the operation of said card-receiving means according to the position of the record holes in said cards.

5. In a card-handling machine, in combination, means for holding a quantity of cards having record holes punched in different positions therein, means for assorting 100 said cards comprising an ejector, card-transferring means and card-receiving means, 105 and a pneumatic controlling mechanism operating through the record holes punched in said cards and adapted to control the operation of said card-receiving means according to the position of the record holes in said 110 cards, said automatic controlling mechanism being adjustable to different positions, for the purpose indicated.

6. In a card-handling machine, in combination with card assorting mechanism, pneumatic means for controlling the same, said pneumatic means operating automatically, and controlled by record holes through said 115 cards.

7. In a card-handling machine, in combination with means for moving cards having record holes punched therethrough and means for selectively receiving the same, of pneumatic means operating through the record holes in said cards for controlling the 120 operation of card receiving means.

8. In a card-handling machine for handling cards having record holes punched therein, in combination, card-holding means, card-ejecting means, card-moving means, a 130

- plurality of card-receiving means, and pneumatic means operating through record holes in said cards for controlling said card-receiving means, said card-receiving means being automatically and pneumatically selected according to the position of the record holes in said cards. 65
9. In a card assorting machine, in combination, means for holding a series of cards 10 having record holes punched in various positions, means for ejecting said cards therefrom one by one, a series of card-receiving pockets, means for moving said ejected cards thereto, means for directing said cards into 15 the different pockets, and pneumatic means operating through the record punches in said cards for selectively controlling the operation of said directing means according to the positions of the record punches in said 20 cards. 80
10. In a card-assorting machine, in combination, a card holder, a card ejector, a card assorting mechanism, pneumatic means for controlling the operations of said card ejector and said card-assorting mechanism, and a series of cards having record holes punched therethrough in different positions, said cards being adapted to control the operation of said pneumatic means according to the 25 position of the record holes therein. 90
11. A card-assorting machine comprising in combination a card holder, a series of cards having record holes punched therein, a card ejector, card-moving means, a plurality of card-receiving pockets, selective means for directing cards into said pockets, and pneumatic controlling means operating through the record punches in said cards for controlling the operation of the selective 35 means for directing said cards into said pockets, the position of the record hole in the card determining the pocket into which said card is deposited. 95
12. A card-assorting machine comprising 40 in combination a card holder, a series of cards having record holes punched therein, a card ejector, card-moving means, a series of receiving pockets, selective switching members for directing the cards into said 45 pockets, operating keys with operating connections therefrom for controlling the operation of said switching means, and pneumatic operating connections therefrom for controlling the operation of said switching means, 50 and pneumatic operating means, controlled by the record punches in said cards, for selectively operating said keys, whereby the record punches in said cards determine the pocket into which said cards are deposited. 55
13. A card-assorting machine comprising 60 in combination a card holder, a series of cards having record holes punched therein, a card ejector, card-moving means, a series of receiving pockets, selective switching 65 members for directing the cards into said pockets, operating keys with operating connections therefrom for controlling the operation of said switching means, and pneumatic operating connections therefrom for controlling the operation of said switching 70 means, and pneumatic operating means, controlled by the record punches in said cards, for selectively operating said keys, whereby the record punches in said cards determine the pocket into which said cards are deposited, said pneumatic operating means being adapted to be moved out of operating position relative to said keys, whereby the latter can be manually operated, substantially as described. 75
14. In a card-handling machine, in combination, means for holding a series of cards having record holes punched therethrough, means for ejecting and assorting the same, keys for selectively controlling the operation of said ejecting and assorting means, and a pneumatic selective mechanism operable through the record holes in said cards for selectively operating said keys according to the positions of said record holes. 80
15. In a card-handling machine, in combination, means for holding a series of cards having record holes punched therethrough, means for ejecting and assorting the same, keys for selectively controlling the operation of said selecting and assorting means, and a pneumatic selective mechanism operable through the record holes in said cards for selectively operating said keys according to the positions of said record holes, said pneumatic selective mechanism being adjustable relative to said keys. 90
16. In a card-assorting machine, a support for the cards, a series of cards having record holes punched therethrough, a magnetic ejector for discharging the cards one at a time, receivers for the cards, switches for deflecting the cards into the desired receivers, key-controlled means adapted upon depression of the key to eject a card and set the desired switch, and pneumatic operating means adapted to selectively depress said keys, said pneumatic operating means being controlled by the position of the record holes in said cards. 100
17. In a machine of the character described, a card container adapted to hold cards having record holes therein, a magnetically-operated ejector adapted to individually discharge the cards, and pneumatic means operable through the record holes in said cards for controlling said magnetically-operated ejector. 110
18. In a machine of the character described, a card container adapted to hold cards having record holes therein, a magnetically-operated ejector for the cards, pneumatic means operable through the record 120

holes in said cards for controlling the operation of said ejector, a plurality of distributing pockets, and switches to deflect the cards to their appropriate pockets, said switches being connected to be also actuated by said pneumatic controlling means.

19. In a machine of the character described, a card container adapted to hold the cards to be distributed, a series of cards having record holes punched in different positions therein, means for ejecting the cards individually, card-moving means, a plurality of distributing pockets, switches adapted to deflect the cards to their appropriate pockets, a series of actuators operable to throw the appropriate switch and operate the ejector to discharge a card, and pneumatic means controlled by the record holes in said cards for selectively operating said actuators.

20. In a machine of the character described, a container for the cards to be distributed, a series of cards having record holes therein, distributing means, and selective, pneumatically controlled devices for simultaneously ejecting a card and determining its place of distribution according to the position of the record hole in said card.

21. In a card-handling machine, in combination, card-holding means, a series of cards having record holes punched therethrough in different positions, ejecting means for ejecting said cards individually, means for operating the same, and pneumatic means for automatically controlling the operation of said ejecting means.

22. In a card-handling machine, in combination, a card holder, a series of cards having record holes therethrough, a series of card receiving pockets, card-ejecting means, card-moving means, means for directing the cards into different pockets according to the information indicated thereon, manually operable devices with operating connections to said card-ejecting means and to said card-directing means for simultaneously ejecting a card and determining its place of distribution, and pneumatic operating means controlled by the record holes in said card for selectively operating said manually operable devices at will.

23. In a card-handling machine, in combination, a card holder, a magnet-operated ejector, card moving means, magnetically-operated card assorting means, operating devices with electrical connections to said magnet-operated ejector and to said magnetically-operated card assorting means, whereby the operation of one of said operating devices simultaneously operates said ejector and the corresponding card assorting means, and means for automatically and pneumatically operating said operating devices.

24. In a card-handling machine, a con-

tainer for the cards to be distributed, ejecting means, distributing means, selective, manually-operable devices, each adapted to effect coöperative electrical communication between the ejecting means and the distributing means, whereby both the ejection of a card from the container and the determining of its place of distribution is effected by the actuation of one of the manually operable devices, and automatic pneumatic devices, whereby to make said card-handling machine automatic at will.

25. In a card-handling machine, in combination, with cards having record holes punched therethrough, pneumatic controlling means for said machine, said pneumatic controlling means being controlled by said cards and the record holes therethrough, said pneumatic means operating through said record holes.

26. Pneumatic controlling means for card-handling machines comprising means having air passageways therethrough, means for passing air through said passageways, actuating members movable by said air, and cards having record holes therethrough and adapted to be interposed in said air passageways, whereby the record holes therein determine which actuating member is operated.

27. In a card-handling machine, electrically operated card-assorting mechanisms, and pneumatically operated means for controlling the same, said pneumatically operated means being adapted to be controlled by the cards to be assorted.

28. In a card-handling machine, magnetically operated card-handling mechanisms, circuit connections therefor with circuit controlling devices interposed therein, and pneumatically operated means for operating said circuit controlling devices, said pneumatic operating means being adapted to be controlled by the cards to be handled, whereby to selectively operate said circuit controlling devices.

29. In a card-handling machine, electrically operated card-ejecting and card-assorting mechanisms, cards having record holes punched in different positions therethrough, and pneumatic means operable through said record holes in said cards and controlled thereby for automatically and selectively controlling the operation of said card-ejecting and said card-assorting mechanisms.

30. In a card-handling machine, in combination, a card holder, a card ejector, card-moving means, a series of receiving pockets having switches for directing cards thereto, means for operating all of said mechanisms, means for momentarily stopping said cards after they have been ejected from said card holder, and pneumatic controlling

means, the operation of which is controlled by said cards in their stopped position, whereby said pneumatic controlling means automatically determines the pocket into which said card is to be deposited.

31. In a card-handling machine, in combination, a card holder, a magnetically operated ejector, card-moving means with means for operating the same, a series of 10 receiving pockets, magnetically operated switches therefor, controlling devices with circuit connections to said magnetically operated mechanisms, whereby the actuation of one of said controlling devices causes the 15 operation of said ejector and a corresponding pocket switch, electrically operated means for momentarily stopping said cards during their travel toward said pockets, and pneumatically operated means controlled by 20 said card in its stopped position for selectively operating said controlling devices.

32. In a card-handling machine, in combination with a series of cards having record holes punched therethrough, pneumatic 25 means for determining the disposition of said cards controlled by the positions of the record holes in said cards.

33. In a card-handling machine, in combination with a series of cards having record holes punched therethrough, pneumatic 30 means for determining the disposition of said cards controlled by the positions of the record holes in said cards, said means being adjustable to different positions relative to 35 said cards.

34. In a card-handling machine, in combination with a series of cards having record holes punched therethrough, means for moving said cards, and means for stopping 40 said cards, and pneumatic means for determining the disposition of said cards, said pneumatic means being controlled by said cards in their stopped position by the positions of the record holes in said cards.

45. 35. In a card-handling machine, in combination with a series of cards having record holes punched therethrough, means for moving said cards, and means for stopping said cards, and pneumatic means for determining 50 the disposition of said cards, said pneumatic means being controlled by said cards in their stopped position by the positions of the record holes in said cards, said pneumatic means being adjustable relative 55 to the stop position of said cards.

36. In a card-handling machine adapted for handling cards having record holes punched therethrough in different positions, a pneumatic controlling mechanism therefor 60 having a part provided with a series of air passageways therethrough, a part provided with a pocket in its face common to all of said passageways, means for moving a card between said parts, whereby its record hole 65 connects one of said passageways with said

pocket, and means for passing air through said pocket, the record hole in said card, and the passageway in register therewith, for the purpose referred to.

37. In a card-handling machine adapted 70 for handling cards having record holes punched therethrough in different positions, a pneumatic controlling mechanism therefor having a part provided with a series of air passageways therethrough, a part provided with a pocket in its face common to all of said passageways, means for moving a card between said parts, whereby its record hole connects one of said passageways with said pocket, means for adjusting said parts together relative to the card position, and means for passing air through said pocket, the record hole in said card, and the passageway in register therewith, for the purpose referred to. 85

38. In a card-handling machine, means for holding cards, a series of cards having information indicated thereon both by holes and prints, card distributing mechanism with manually operable means for actuating 90 the same according to the printed record, and pneumatically-operated means, controlled by the holes in said cards, for actuating said card-distributing mechanism.

39. In a card-assorting machine, card 95 holding means, card-ejecting means, card-assorting means, a series of cards having information indicated thereon both by holes and prints, manually operable means for controlling the actuation of said mechanisms according to the print on said cards, and pneumatic means, controlled by the holes in said cards, for actuating said mechanisms. 100

40. In a card-handling machine, in combination, card-holding means, a series of cards having information indicated thereon both by holes and prints, electrically-operated ejecting means, card-moving means, electrically-operated card-directing means, a 105 series of manually operable controlling devices with electrical connections to said card-ejecting means and to said card-directing means for controlling the disposition of said cards according to the printed record 110 thereon, and pneumatically-operated means, controlled by the holes in said cards, for determining the disposition of said cards according to the holes therein, substantially as described. 115

41. In a card-handling machine, in combination, card-holding means, a series of cards having information indicated thereon both by prints and holes therein, electrically-operated card-ejecting means, card-moving 125 means, with means for operating the same, electrically-operated card-stopping means, electrically-operated card-directing means, card-receiving means, manually-operable controlling devices with electrical connec- 130

tions therefrom to said card-ejecting card-stopping and card-directing means, for controlling the disposition of said cards into said card-receiving means according to the prints thereon, and pneumatically-operated means, controlled by the holes in said cards, for determining the disposition of said cards into said card-receiving means according to

the holes therein, substantially as described.
Signed at Portland, Multnomah county, 10
Oregon, this 2 day of May, 1917.
